UNITED STATES PATENT OFFICE.

CHARLES WILLIAM PRADEAU, OF SHEPHERD'S BUSH, LONDON, ENGLAND.

CLUTCH.

No. 902,999.

Specification of Letters Patent.

Patented Nov. 3, 1908.

Application filed October 7, 1907. Serial No. 396,307.

To all whom it may concern:

Be it known that I, CHARLES WILLIAM PRADEAU, a subject of the King of England, residing at 1 Stowe Road, Shepherd's Bush, in the county of London, England, have invented certain new and useful Improvements in Clutches; and I do hereby declare the following to be a full, clear, and exact description of the invention, such as will enable others skilled in the art to which it appertains to make and use the same.

This invention relates to an improved clutch applicable to engines and other purposes.

This invention has reference to that class of clutches in which a drum is connected to the driving shaft and in the interior of which is placed two similar segmental pieces, so placed that their ends come equidistant from the diametrical line. In the space between the ends of the segmental pieces are fitted cams, preferably of oval form. These cams are so fitted that when they are in one position the segmental pieces shall be forced tightly against the sides of the drum so as to form a frictional clutch and rotate the said pieces and consequently the mechanism connected therewith.

According to this invention the axes of the cams are in the same plane as the axis of the shaft and at right angles thereto. When the cams are in another position the drum will be free to work round the said segmental pieces, these remaining stationary. The said cams are actuated by means of a foot lever or otherwise according to the purposes for which the clutch is employed. And in order that my said invention may be understood I will proceed to describe the same with reference to the drawing accompanying this specification, which shows my invention as applied to the engine of a motor car.

Figure 1 shows a sectional elevation of the clutch. Fig. 2 shows a top plan view of the same. Fig. 3 shows a section through the line A, B, Fig. 2. Fig. 4 shows a detail hereinafter referred to.

The same letters of reference are employed to denote the same parts in all the views.

a shows a drum, which may be bolted to the fly wheel of the engine by means of the flanges b.

c are segmental pieces placed loosely in the drum a leaving a space d between the ends of such segmental pieces in diametrical positions.

e shows cams fitted in the spaces d. The cams e are mounted on or formed with spindles f, the axes of which are at right angles to the axis of the shaft n working in bearings g. To the spindles f are secured the arms h. The ends of these arms h are pivoted together through a link piece i, which link piece i is pivoted at its other end to an arm k fixed to or formed with a sleeve m mounted loosely on a shaft n. To the top of this shaft n is keyed a disk o bearing on the top of the segmental pieces c. Round the sleeve m is adjustably fixed a collar p having a groove cut round same. In this groove are placed two semi-circular pieces q having at their extremities half a bolt as shown in detail at Fig. 4, so that when they are in position a complete bolt is formed at each side of the pieces q. Over the ends of the bolts is passed an arm r secured in position by means of a nut s. This arm r forms one end of a cantaliver pivoted at t and at the other end is provided a foot plate u. v shows a spiral compression spring placed on the shaft n held in position at one end by means of the sleeve m and the other end by means of a nut w.

The action is as follows:—Supposing the mechanism to be in the clutched position as shown at Fig. 1, it is retained in this position by means of the spring v. Upon depressing the foot plate u the lever r is drawn downwards bringing with it the sleeve m and consequently the arm k, which being connected to the arms h by means of the link i causes the cams to turn in the direction of the arrow, Fig. 1, thus taking off the pressure on the ends of the segmental pieces c and likewise the friction between the interior of the drum a and such segmental pieces, thus stopping the rotation of the shaft n. Upon releasing the pressure on the plate u the clutch is brought back to its normal position.

If it is desired to adjust the pressure of the spring v, owing to the wear on the cams or ends of the segmental pieces, this can be done by means of the nut w.

What I claim and desire to secure by Letters Patent of the United States of America, is:—

1. In a friction clutch the combination of a hollow drum, a driving shaft, segmental pieces mounted on said shaft, and adapted to frictionally engage the interior of said drum, cams provided with spindles extending at right-angles to the axis of the shaft, said cams being located between said segmental

pieces, bearings for said spindles, arms secured to said spindles, a link piece pivoted to said arms, an arm to which said link piece is pivoted, a sleeve rigid with said last mentioned arm, a collar adjustably fixed to said sleeve, said collar provided with a groove, semicircular pieces *q* provided with half bolts at each extremity fitting said groove, causing said half bolts to form complete bolts, and 10 means fitting said complete bolts, adapted to move the same up and down, substantially as described.

2. In a friction clutch the combination of a hollow drum, a driving shaft, segmental 15 pieces mounted on said shaft, and adapted to frictionally engage the interior of said drum, cams provided with spindles extending at right-angles to the axis of the shaft, said cams being located between said segmental

pieces, bearings for said spindles, arms secured to said spindles, a link piece pivoted to said arms, an arm to which said link piece is pivoted, a sleeve rigid with said last mentioned arm, a collar adjustably fixed to said sleeve, said collar provided with a groove, 25 semicircular pieces *q* provided with half bolts at each extremity fitting said groove, causing said half bolts to form complete bolts, an arm *r* secured to said complete bolts, a lever connected to said arm and a foot plate rigid 30 with said lever, substantially as described.

In testimony whereof, I affix my signature in presence of two witnesses.

CHARLES WILLIAM PRADEAU.
